DOOR HINGE

Charles A. Kirby, Rte. 2, Box 2242, Gig Harbor, Wash.

Filed July 6, 1965, Ser. No. 86,024

Term of patent 14 years

(Cl. D10—9)

FIG. 1.

FIG. 2.

FIG. 4.

FIG. 3.

FIG. 6.

FIG. 5.

FIG. 1 is a back plan view of the door hinge, showing my new design;

FIG. 2 is a view in end elevation of the hinge;

FIG. 3 is a front plan view of the hinge;

FIG. 4 is a view in side elevation of the hinge;

FIG. 5 is a front plan view of the hinge in an alternate embodiment; and

FIG. 6 is a view in side elevation of the hinge of FIG. 5.

I claim:

The ornamental design for a door hinge, as shown and described.
